UNITED STATES PATENT OFFICE.

MOLLY G. GRODNICK, OF MINNEAPOLIS, MINNESOTA.

COLLAPSIBLE RECEPTACLE.

Application filed August 26, 1924. Serial No. 734,172.

To all whom it may concern:

Be it known that I, MOLLY G. GRODNICK, a citizen of the United States, residing at Minneapolis, in the county of Hennepin and 5 State of Minnesota, have invented certain new and useful Improvements in Collapsible Receptacles, of which the following is a specification.

This invention relates to collapsible containers and the main object is to provide a receptacle of a neat and compact character which may be conveniently used, for instance, as a lunch box, vanity case or as a case for money, personal effects, etc., the 10 uses to which it may be put being limited only by the size and proportions embodied in the device, and the wishes of the owner. Further and more specific objects will be disclosed in the course of the following 15 specification, reference being had to the accompanying drawing, in which:

Fig. 1 is a perspective view of the device, as seen when in a partly open or spread out condition.

Fig. 2 is an enlarged transverse sectional view of the device, as seen when collapsed.

Fig. 3 is an enlarged transverse sectional view of the device, as when set up as a container.

Fig. 4 is an enlarged detail perspective view showing the corner securing means.

Referring to the drawing more particularly and by reference characters 5 designates a shallow base section having marginal 35 end flanges 6 and side flanges 7 and 8. A pair of end sections 9 are hingedly secured to the end flanges, and are provided with edge flanges 10, which, with the end sections fold 40 into the base section when the device is collapsed. The side sections consist of a front section 11, hinged to the flange 7, and a back section 12, hinged to the base flange 8. The sections 11 and 12 are provided with fasteners 13, which are arranged to detachably 45 engage in slots 14 in the flanges 10, to secure the four sections 9, 9, 11 and 12 together in rigid vertical positions.

The cover section consists of a pair of sheet metal members 15 and 16, hingedly connected together as at 17. A flexible cover member 18, which is secured to and extends from the back section 12, is glued or otherwise suitably secured to the entire outer surface of the member 15, but is not 55 secured to the member 16, so that the latter may be folded away from the cover member

and against the member 15 (see Fig. 2), when so desired, thus leaving a flexible strap connection between the near edges of the members 12 and 15. From the outer edge 60 of the top section 15 the flexible cover member continues in a portion 18^a which is creased or folded at 19, when the device is collapsed, and at 20, when it is set up.

A small coin purse 21 and mirror 22 may 65 be secured to the inner side of the member 18^a, if so desired. A snap fastener 23, near the outer edge of the flap 18^a, is arranged to releasably engage a co-operating member 24, when the case is collapsed, and a similar 70 member 25, when the device is set up. A handle 26 is provided whereby the device may be carried either when set up or collapsed.

When the device is set up, as in Fig. 3, 75 it will be obvious that a complete sheet metal enclosure is provided, the fabric or flexible portion serving only to bind the parts together in an efficient and practical manner, as well as serving to add greatly 80 to the appearance of the container. When the device is to be collapsed, the fastener 23 is released from the member 25, the top 15—16 and flap 18^a are folded back, the fasteners 13 are then released from the slots 85 14, after which the end sections 9 are folded into the base, the front section 11 is folded down upon the end sections, the member 16 is folded against the member 15, (to permit the flexible portion 18 to be pulled 90 over the base, as in Fig. 2), the top 15 is folded down and the end flap 18^a is pulled around until the fastener 23 can be snapped into engagement with the member 24. The device as collapsed has the appearance of a 95 neatly formed and attractive ladies' purse, and is therefore very desirable for that reason as well as for the reasons which have already been stated.

It is understood that various modifications 100 may be made in the general design and structural details of the invention as herein disclosed, provided, however, that such modifications come within the spirit and scope of the appended claims. Having now therefore fully shown and described my invention, what I claim to be new and desire to protect by Letters Patent is:

1. A collapsible receptacle consisting of 110 a base, side and end sections hingedly secured to the base, a flexible cover member adapted to substantially enclose the receptacle when

the latter is collapsed, a sheet metallic top section adapted to close the receptacle when set up, said top section being secured to the cover member and being jointed, as and 5 for the purpose set forth.

2. A collapsible receptacle consisting of a base, inwardly foldable side and end sections secured to the base, means for detachably securing the side and end sections 10 in a vertical position, a cover member ex-

tending at one end from one of the side sections, and adapted to be secured with its other end to the receptacle, a top section, secured to the cover member, for closing the receptacle when set up, said top section consisting of a pair of hingedly connected sheet metal members. 15

In testimony whereof I affix my signature.

MOLLY G. GRODNICK.
